CLAIM

An ornamental design for a nugget keychain, as shown and described.

DESCRIPTION

FIG. 1 is a front perspective view of a nugget keychain; FIG. 2 is a front elevational view of the keychain of FIG. 1; FIG. 3 is a rear elevational view of the keychain of FIG. 1; FIG. 4 is a right-side elevational view of the keychain of FIG. 1; FIG. 5 is a left-side elevational view of the keychain of FIG. 1; FIG. 6 is a top view of the keychain of FIG. 1; and, FIG. 7 is a bottom view of the keychain of FIG. 1. The broken lines shown as dashed lines are for the purpose of illustrating unclaimed structure, and form no part of the claimed design.
